REEL FOR FLY FISHING

Gary R. Oberg, Spirit Lake, Iowa, assignor to
Berkley & Company, Inc., Spirit Lake, Iowa

Filed Aug. 1, 1974, Ser. No. 493,986

Term of patent 14 years

Int. Cl. D22—05

U.S. Cl. D22—25

FIG. 1

FIG. 2

FIG. 8

FIG. 6

FIG. 7

FIG. 4

FIG. 3

FIG. 1 is a perspective view showing one side and end of a reel for fly fishing;

FIG. 2 is a perspective view showing the opposed side and opposite end of the reel for fly fishing of FIG. 1;

FIG. 3 is a side elevational view showing that side of the reel for fly fishing illustrated in FIG. 1;

FIG. 4 is an end view of the reel for fly fishing, showing the forward end of the reel as viewed in the perspective of FIG. 1;

FIG. 5 is a side elevational view of the reel for fly fishing, showing the same side as is illustrated in FIG. 2, and opposed to that illustrated in FIG. 3;

FIG. 6 is a bottom plan view of the reel for fly fishing;

FIG. 7 is a top plan view of the reel for fly fishing; and

FIG. 8 is an end elevational view of the reel for fly fishing, and illustrating the end which is visible in FIG. 2, and opposed to that shown in FIG. 4.

I claim:

The ornamental design for a reel for fly fishing, as shown.
